UNITED STATES PATENT OFFICE

GUY E. GRAYBILL, OF OAK PARK, ILLINOIS

DESIGN FOR A DISPLAY STAND

Application filed May 27, 1931. Serial No. 40,013. Term of patent 3½ years.

To all whom it may concern:

Be it known that I, GUY E. GRAYBILL, a citizen of the United States, residing at Oak Park, in the county of Cook and State of Illinois, have invented a new, original, and ornamental Design for a Display Stand, of which the following is a specification, reference being had to the accompanying drawing forming part hereof, and showing a perspective view of a display stand embodying my new design.

I claim:

The ornamental design for a display stand, substantially as shown.

GUY E. GRAYBILL.
